UNITED STATES PATENT OFFICE.

HOWARD F. SNYDER, OF NEWTON, IOWA, ASSIGNOR TO MAGTAG COMPANY, OF NEWTON, IOWA, A CORPORATION OF IOWA.

WASHING MACHINE.

Application filed July 24, 1920. Serial No. 396,678.

To all whom it may concern:

Be it known that I, HOWARD F. SNYDER, a citizen of the United States, residing at Newton, in the county of Jasper and State 5 of Iowa, have invented certain new and useful Improvements in Washing Machines, of which the following is a specification.

This invention relates primarily, though not exclusively, to small machines particularly adapted for the doing of small washings, such as handkerchiefs, stockings, and other small articles of clothing.

Among the objects of my invention are to provide a new type of machine adapted 15 for use in apartments and other places of limited space, where existing machines are too cumbersome; to produce an electrically driven washing machine, which can be sold at a comparatively small price, so as to 20 be within the reach of the large majority of people; to provide a machine so compact and light in construction that it may be readily attached to a bath tub, and which when attached will not occupy any floor 25 space in addition to that already occupied; to produce a machine which may be used in connection with other stationary water receiving equipment of a house or apartment, such, for example, as a sink; to provide 30 a motor driven machine suitable for use by school girls, clerks, teachers, mothers, and others having small or fine washings to do, including such things as stockings, 35 waists, lace curtains and children's clothing; to provide a machine which can be easily so arranged that no carrying of water to or from the machine is necessary; to construct a machine such that it is unnecessary for the user to at any time put her 40 hands in the hot water in the machine; and such further objects, advantages and capabilities as will later more fully appear.

My invention further resides in the combination, construction, and arrangement of 45 parts illustrated in the accompanying drawings and while I have shown therein preferred embodiments I desire the same to be understood as illustrative only and not as limiting my invention.

50 In the accompanying drawings illustrating my invention, Fig. 1 is a perspective view of my machine attached to a bath tub, Fig. 2 is an elevation of my machine partly broken away to show the interior thereof, 55 Fig. 3 is a transverse section through the

tub and machine shown in Fig. 1, Fig. 4 shows a somewhat modified form of my invention, adapted for use in another location, and Fig. 5 is an elevation of the structure shown in Fig. 4.

60 Referring more in detail to the drawings, numeral 1 designates in general the washing cylinder of the washing machine, comprising the body portion 2 and the cover 3 hinged at 4 and held in closed relation by a fastening device 5. These parts are provided as shown in Fig. 3 with flanges at their meeting edges, and to the flange on one of these parts is secured a gasket 6 of suitable size and shape to form 70 a water tight joint between these parts when they are secured in closed relation.

75 In the middle of one end the cylinder is indented as shown at 7, and has extending therefrom a boss 8, which may terminate substantially in the plane of that side of the machine. Passing thru this boss and secured therein is a shaft 9, which is mounted in a similar boss 10 on frame 11, which carries the electric motor 12 adapted 80 to drive the cylinder. Suitable gearing 13 connects the motor 12 with the cylinder 1, which has, arranged concentrically with relation to the boss 8, a flange 14 which is provided with gear teeth adapted to mesh 85 with the driving gearing 13.

Attached to the frame 11 is a pair of 90 rubber covered supporting arms 15. These are shaped so that they can be hooked over the edge of a bath tub to hold the machine 95 supported thereon. Carried by the lower end of the frame 11 is a resilient member 16, preferably of rubber, adapted to prevent chipping of the enamel and to assist in reducing the amount of vibration of the tub, which might result from having the metal of the machine resting directly against the bath tub wall.

100 In the form shown in Figs. 4 and 5, legs 20, connected to a frame 21, support the same above any convenient drainage place 22, such as a sink. The cylinder 1 is supported by a pair of trunnions 23 on the casing 21. A motor 12, actuating driving gear 13, rotates the cylinder upon its trunnions, thus causing the clothing within the cylinder to be washed. It is immaterial 105 whether the gearing on the flange 14 is external as shown in Fig. 3 or internal as shown in Fig. 5. The casing 21 prevents 110

the splashing of water and consequent wetting of the floor when the cylinder cover 3 is opened and the cylinder turned over to empty the water therefrom.

- 5 Either of the forms described above may be provided with a pivoted gate as shown at 24 in Figs. 2 and 3. This gate is supported on a rod 25 which has secured to one end thereof a handle 26, by means of 10 which it may be rotated to place the gate in the dotted line position shown in Fig. 3. It will be noted that the cylinder is provided upon one side with a recess into which the gate is swung in order to get the same 15 out of the way while the washing machine is being used.

The purpose of shelf 24 is to support the clothes outside of the hot water and to permit the same to drain therefrom so 20 that the operator may remove the clothes from the cylinder without putting her hands into the water, thus getting scalded. To use this shelf the operator would first turn the machine with the cover down, then turn 25 the shelf into position across the cylinder, and then turn the cylinder until the cover is up. The water will now drain from the clothes and it will be found when the cover is opened that the clothes can be picked 30 up without putting the hands into water.

Subject matter disclosed but not claimed herein is claimed in my co-pending divisional application Serial No. 498,113, filed September 2, 1921.

35 It is, of course, understood that the specific description of structure set forth above may be departed from without departing from the spirit of my invention as set forth in this specification and the appended claims.

Having now described my invention,

I claim:

1. In a machine of the character described, a rotatably mounted cylinder provided at one end with a hollow protuberance opening toward the interior of the cylinder, and a gate mounted in said hollow protuberance and adapted to be swung inwardly across the cylinder to form a 45 shelf therein.

2. In a machine of the character described, a cylinder, a support therefor, means for rotating said cylinder on said support, supporting means within the cylinder, a part of which, at least, is pivoted to swing 50 against one end of the cylinder, and means external to the cylinder for moving the pivoted part about its axis.

3. In a washing machine, a clothes washing cylinder comprising two part cylinders 60 hinged together, the meeting edges of said parts having reinforcing flanges being provided with complementary grooves, a gasket secured in one of said grooves and extending into the other of said grooves, 65 and means for securing the parts of the cylinder tightly together to prevent leakage when rotating.

4. In a machine of the character described, a cylinder having one section thereof pivoted to form a cover, a gate pivoted within the cylinder to form a support for clothes so that same may be held supported above water in the cylinder, and means 70 for supporting the cylinder.

In witness whereof, I hereunto subscribe my name to this specification in the presence of two witnesses.

HOWARD F. SNYDER.

the splashing of water and consequent wetting of the floor when the cylinder cover 3 is opened and the cylinder turned over to empty the water therefrom.

5 Either of the forms described above may be provided with a pivoted gate as shown at 24 in Figs. 2 and 3. This gate is supported on a rod 25 which has secured to one end thereof a handle 26, by means of 10 which it may be rotated to place the gate in the dotted line position shown in Fig. 3. It will be noted that the cylinder is provided upon one side with a recess into which the gate is swung in order to get the same 15 out of the way while the washing machine is being used.

The purpose of shelf 24 is to support the clothes outside of the hot water and to permit the same to drain therefrom so 20 that the operator may remove the clothes from the cylinder without putting her hands into the water, thus getting scalded. To use this shelf the operator would first turn the machine with the cover down, then turn 25 the shelf into position across the cylinder, and then turn the cylinder until the cover is up. The water will now drain from the clothes and it will be found when the cover is opened that the clothes can be picked up without putting the hands into water.

Subject matter disclosed but not claimed herein is claimed in my co-pending divisional application Serial No. 498,113, filed September 2, 1921.

35 It is, of course, understood that the specific description of structure set forth above may be departed from without departing from the spirit of my invention as set forth in this specification and the appended claims.

Having now described my invention,

I claim:

1. In a machine of the character described, a rotatably mounted cylinder provided at one end with a hollow protuberance opening toward the interior of the cylinder, and a gate mounted in said hollow protuberance and adapted to be swung inwardly across the cylinder to form a shelf therein. 45

2. In a machine of the character described, a cylinder, a support therefor, means for rotating said cylinder on said support, supporting means within the cylinder, a part of which, at least, is pivoted to swing 55 against one end of the cylinder, and means external to the cylinder for moving the pivoted part about its axis.

3. In a washing machine, a clothes washing cylinder comprising two part cylinders 60 hinged together, the meeting edges of said parts having reinforcing flanges being provided with complementary grooves, a gasket secured in one of said grooves and extending into the other of said grooves, 65 and means for securing the parts of the cylinder tightly together to prevent leakage when rotating.

4. In a machine of the character described, a cylinder having one section thereof pivoted to form a cover, a gate pivoted within the cylinder to form a support for clothes so that same may be held supported above water in the cylinder, and means for supporting the cylinder. 70

In witness whereof, I hereunto subscribe my name to this specification in the presence of two witnesses.

Certificate of Correction.

It is hereby certified that the name of the assignee in Letters Patent No. 1,526,020, granted February 10, 1925, upon the application of Howard F. Snyder, of Newton, Iowa, for an improvement in "Washing Machines," was erroneously written and printed as "Magtag Company," whereas said name should have been written and printed as *Maytag Company*, as shown by the records of assignments in this Office; and that the said Letters Patent should be read with this correction therein that the same may conform to the record of the case in the Patent Office.

Signed and sealed this 28th day of April, A. D. 1925.

[SEAL.]

KARL FENNING,
Acting Commissioner of Patents.
